(57) **CLAIM**

The ornamental design for a vehicle rear portion, as shown and described.

DESCRIPTION

FIG. 1 is a perspective view of a vehicle rear portion showing our new design;

FIG. 2 is a side elevational view of one side thereof;

FIG. 3 is a side elevational view of the other side thereof; and,

FIG. 4 is a rear elevational view thereof.

The broken line showings of the wheels, tires and lozenge shape, and the remainder of the vehicle exterior form no part of the claimed design.

1 Claim, 4 Drawing Sheets
